DOUBLE-BREASTED DRESS VEST

Charles Emms, London, England

Application May 29, 1953, Serial No. 25,251

Term of patent 7 years

(Cl. D3—4)

To all whom it may concern:

Be it known that I, Charles Emms, a subject of the Queen of Great Britain, residing at 17 Savile Row, W. 1, London, England, have invented a new, original, and ornamental Design for a Double-Breasted Dress Vest, of which the following is a specification, reference being had to the accompanying drawing, forming part thereof.

In the drawing:

I claim:

The ornamental design for a double-breasted dress vest, as shown.

CHARLES EMMS.
